LUBRICANT TRANSFER FOR MULTICOMPARTMENT CRANK CASES

Filed Sept. 24, 1923

FIG. 1

FIG. 3

FIG. 2

INVENTOR

ALFRED C. ELLEY
BY *Ray McElroy*

ATTORNEY

UNITED STATES PATENT OFFICE.

ALFRED C. ELLY, OF BELOIT, WISCONSIN, ASSIGNOR TO FAIRBANKS, MORSE & CO.,
OF CHICAGO, ILLINOIS, A CORPORATION OF ILLINOIS.

LUBRICANT TRANSFER FOR MULTICOMPARTMENT CRANK CASES.

Application filed September 24, 1923. Serial No. 664,453.

My invention relates to improvements in lubricant transfers for multi-compartment crank cases, and more particularly to a means for transferring lubricating oil from compartment to compartment in the crank case of engines operating with crank case compression.

The object of my invention is to provide means of simple and inexpensive construction 10 for the movement of lubricating oil from compartment to compartment in a multi-cylinder engine.

Heretofore the oil has been conveyed from the compartments in the crank case of multi-cylinder engines to the lubricating system by means of external drains. This means presents the objections of being easily obstructed and of being subject to damage. My system obviates these difficulties since it is internal to 20 the crank case and not easily obstructed, as will be shown. Other advantages will be evident from the description.

My improvements consist in the construction, arrangement and combination of parts, 25 as hereinafter fully and clearly and concisely described and illustrated by the accompanying drawings, in which Fig. 1 shows in longitudinal, sectional elevation an engine crank case having a plurality of compartments 30 equipped with an oil transfer embodying my improvements.

Fig. 2 shows an enlarged detail sectional elevation, a fragment of a crank case comprising one of the dividing walls and a transfer for oil, and Fig. 3 shows an alternate form 35 of oil transfer.

In Fig. 1, 4 is a crank case, divided into compartments A, B, C and D, by means of the walls 5. Adjacent the bottom of the 40 crank case each wall 5, is preferably provided with a passageway 6, to place the compartments in communication. The passageways 6, are so disposed as to place their inlets 7, in planes beneath their outlets 8, this in order 45 to control the direction of oil flow so as to obtain, for example, a successive transfer from A to B, B to C, and from C to D.

A pump, 15, here shown as a plunger pump, but which may be of any suitable type, is 50 preferably connected to the outlet 8 of the end compartment D for the purpose of removing the oil therefrom. The inlet 7 to this outlet is preferably positioned below the plane of the outlet of passageway 6, leading

into compartment D, for the purpose of 55 maintaining the oil level below said outlet.

The operation of this system of oil transfer is automatic in action. Due to piston 60 positions, engine revolutions per minute and other factors, the pressures in the various compartments fluctuate, hence if there is oil in compartment A covering the inlet 7, of the passageway between compartments A and B, it will be blown through the passageway when the pressure in compartment A is in 65 excess of the pressure in compartment B. Similarly oil will be moved from compartment B to C when the pressure in B is in excess of the pressure in C.

By the expedient of the residence of the 70 outlet 8 of the passageway in a plane above the normal oil level the oil is prevented from movement from outlet 8 to inlet 7, as, for example, oil in compartment B would be prevented from movement to A when the pressure in B becomes greater than in A. 75

In the normal operation of engines of the recited type there would be a reversal of air movements through the passageways at least once during each revolution of the engine, 80 hence the stoppage of the passageways by lodgment of foreign matters in the oil is practically impossible, to the end that such action is self-cleaning and stoppage is reduced to a minimum. 85

In engines having relatively high pressures in the crank cases the transfer of oil from compartment to compartment may be accompanied with spraying at the outlets 8, which is not desirable and which may be prevented 90 by so arranging the shape of the outlets that the oil will be directed against the walls of the compartment. An illustrative arrangement is shown comprising a baffle. The particular baffle here shown consists of a nut 9 95 at the outlet end of the orifice, having one or more lateral openings therein. This is best shown in Fig. 2.

In Fig. 3 the passageway comprises a tube 10 secured in a dividing wall as by a collar 100 11 and screw cap 12, and which comprises all the operative characteristics as recited with the form shown in Figs. 1 and 2.

I do not limit myself in the use of my improvement to two cycle engines and it is readily seen that my system of oil transfer may be used in any multicylinder engine in which a periodically varying pressure exists in the 105

different compartments of the crank case. Though my invention consists largely in the construction and arrangement of parts hereinafter described and particularly pointed out in the claims, yet I do not limit my invention to the precise form or construction of parts shown or the several parts thereof, inasmuch as various alterations may be made without changing the scope of my invention.

10 I claim:

1. A crank case, a vertical dividing wall therein and means forming a valveless conduit for the unidirectional transfer of oil through said wall by crank case pressure.
- 15 2. A crank case, a vertical dividing wall therein, means for the transfer of oil through said wall, an inlet to said means for the transfer of oil, an outlet to said means for transferring oil, said outlet being in a plane above said inlet, the relative locations of the inlet and outlet determining the direction of oil flow.
- 25 3. A crank case, a vertical dividing wall therein, conducting means for the transfer of oil through said wall by crank case pressure, said means having an outlet substantially above the inlet thereof, and a baffle, formed by said conducting means and associated with said outlet.
- 30 4. In a crank case, a compartment wall, a one-way, open oil passage extending therethrough comprising a baffle, adapted to direct the oil toward the compartment wall.
- 35 5. In a crank case having a dividing wall forming a plurality of laterally disposed compartments therein, a conduit through said wall having its outlet located in a plane above its inlet, a passageway through said crank case into one of said compartments having its opening into said compartment located in a

plane below the outlet of the conduit leading into said compartment, and a pump connected to said passageway.

6. In a crank case, a vertical dividing wall therein forming a plurality of crank-case compartments, an oil conduit between said compartments having its inlet located in a plane substantially below its outlet, an outlet from that compartment containing the outlet from said conduit, said outlet from the compartment being resident in a plane below the outlet from said conduit, the arrangement of the inlet and outlets constituting a non-return means adapted to determine the direction of movement of oil through the conduit. 45

7. In a crank case having a plurality of laterally disposed compartments therein, an inlet and an outlet to each of said compartments, connecting means between the outlet of one compartment and the inlet to the succeeding compartment, said outlet being located in a plane below said inlet, and a pump adapted to be connected to the outlet of the last of said compartments. 50

8. In an engine, crank case pressure compartments adapted to contain oil, and conduits for continuous communication therebetween; each of said conduits being so disposed that return of oil therethrough is prevented, and so disposed that the conduit is 60 periodically cleaned by an air current of opposite direction to that of the oil. 65

9. In an engine, crank case pressure compartments and oil-transfer conduits for continuous communication therebetween, one of 70 said conduits providing a non-return means for the oil and a self-cleaning means constituted by locating the outlet of the conduit substantially higher than the inlet thereof. 75

ALFRED C. ELLEY.
